UNITED STATES PATENT OFFICE.

LORENZO DOW GORDON, OF TENAHA, TEXAS, ASSIGNOR OF ONE-HALF TO
GEORGE M. LASSETER AND EDWARD S. HICKS, OF SAME PLACE.

PRESS.

SPECIFICATION forming part of Letters Patent No. 376,300, dated January 10, 1883.

Application filed April 20, 1881. Serial No. 235,514. (No model.)

To all whom it may concern:

Be it known that I, LORENZO DOW GORDON, a citizen of the United States, and a resident of Tenaha, in the county of Shelby and State of Texas, have invented a certain new and useful Improvement in Presses, of which the following is a specification.

This invention has relation to an improvement in lever-powers which is applicable for various purposes, notably for presses for baling cotton, hay, and wool, cider and grape presses, and for presses for expressing oil from cotton-seed and the castor-bean, as also lard-oil from bacon, &c.; and to this end the invention consists of sundry combinations of parts, including their construction, substantially as hereinafter fully set forth, and pointed out in the claims.

In the accompanying drawings, Figure 1 is a plan view of my improved lever-power with the followers under pressure. Fig. 2 is a similar view thereof with the pressure removed from the followers.

In the embodiment of my invention, I employ two levers, A, which are pivoted near their outer ends, as at a , between the parts of a frame, a' , or two sills firmly secured together, and which sills or frame may be connected to a base or support, a'' . The extreme outer ends of these levers carry two toggle-arms, B B, which are also connected to a follower, C, disposed between and transversely to the length of the sills or parts of the frame a , and which rests upon a board, b, and is guided at its upper side in a recess, c, in the under side of the upper sill or part of the said frame, and at its lower longitudinal edges between cleats or strips c', fastened to the board b. C' is a second or main follower, also resting or sliding upon the board b, and guided at its lower longitudinal edges and sides between the same cleats or strips c', forming guides for the follower C and upward extensions c'' of said cleats or strips, while at its upper longitudinal edges it is guided between angular cleats or guides d, fastened or bolted to the upward extensions c'' of the cleats or guides c. This follower C' is connected, also, by two toggle-arms, B' B', to the levers A A, said arms being connected to the follower next its operating end, and to the levers at points somewhat beyond their mid-length on that side thereof next to their

operating ends. The follower C' is recessed at its sides, to permit of the maximum inward movement of the levers A. The levers A A are operated by lines or chains D D', one set 55 of which is connected to a shaft or windlass, E, mounted upon the base or support a'' and to the operating ends of the levers, while the other set of lines or chains, D', is also connected to said shaft or windlass, thence passed around 60 pulleys e e, supported upon the base or support a'' , and also connected to the operating ends of the levers.

One among other ways for conveniently and simultaneously actuating the levers A A 65 through the latter described appliances is by the use of a handled pulley or drum, f, and a belt passed around said pulley or drum, and a second pulley or drum, f', upon the shaft E. The action of the followers is apparent, the 70 same approaching each other, one, however, having a greater movement than the other as the levers are moved toward each other, and thus exerting pressure upon or compressing the article or substance placed or interposed 75 between the followers, while as the levers are separated said followers will be moved apart, releasing the interposed substance and permitting it to be removed or manipulated, as may be required, which operation of parts, it 80 will be observed, underlies the principle of action of the cotton, hay, and wool press, as also presses for expressing oil from the cotton-seed and the castor-bean, as well as presses for obtaining lard-oil from bacon, &c., thus rendering the invention capable of use for any of the 85 aforesaid purposes, among others which it is unnecessary here to mention.

The contrivance can be worked or applied either horizontally or vertically. It exerts a 90 very powerful pressure and may comprise or include additional levers.

Having thus described my invention, what I claim, and desire to secure by Letters Patent, is—

1. In a press, the combination of the manipulating-levers, the followers, and the toggle-arms, of which arms the outer ends of two are connected to the outer ends of the levers, while their inner ends are connected to the sides of 100 the follower near its inner end, and the outer ends of the others are connected to the levers

near their mid-lengths, while their inner ends are connected to the sides of the other follower near its inner end, substantially as and for the purpose set forth.

5. 2. The press comprising two followers and two levers, each of the latter connected by two toggle-arms to said followers, and mechanism for their simultaneous operation, substantially as and for the purpose set forth.

3. The press comprising the coacting followers, each directly connected to levers by two toggle-arms, said levers having connection by chains or lines to a shaft, substantially as and for the purpose specified.

LORENZO DOW GORDON.
